UNITED STATES PATENT OFFICE.

CHARLES DONAT RICHARD, OF NEW BRIGHTON, NEW YORK, ASSIGNOR TO WESTERN ELECTRIC COMPANY, INCORPORATED, OF NEW YORK, N. Y., A CORPORATION OF NEW YORK.

TELEPHONE-EXCHANGE LINE SWITCH.

Application filed September 3, 1920. Serial No. 407,959.

To all whom it may concern:

Be it known that I, CHARLES D. RICHARD, a citizen of France, residing at New Brighton, in the county of Richmond, State of New York, have invented certain new and useful Improvements in Telephone-Exchange Line Switches, of which the following is a full, clear, concise, and exact description.

10 This invention relates to automatic telephone exchange switching apparatus and more especially to line switches of the non-numerical type for automatically connecting subscribers' lines to idle trunks, whereby 15 calls are extended to other switching apparatus which operates to connect calling subscribers' lines to the called lines.

Heretofore one of the obstacles to uninterrupted service which has had to be 20 contended with in automatic telephone systems employing line switches, has been due to the difficulty encountered and excessive time required in removing and replacing individual sets or units of bank terminals when trouble 25 develops therein. This difficulty has been due, most particularly, to the large number of wires required for connecting to the large number of subscribers' line bank terminals and the trunk terminals associated 30 therewith.

One object of the present invention is, therefore, to overcome, as far as possible, the delays incidental to repairs on the terminal banks and this object is accomplished 35 in large measure by the arrangement of banks set forth and described hereinafter.

Co-incidental with the problem of providing a suitable terminal bank to overcome the difficulty before stated, there was the 40 problem of providing an operating mechanism adapted to co-operate with the new arrangement of banks. The provision of such a mechanism is, therefore, the second object of the present invention.

45 In accordance with the above objects, one feature of the invention consists in arranging the banks in four sections, each comprising a plurality of sets of contact springs arranged in a straight row. The four sections being grouped in parallel quadrangular relation, one to the other, about an oper-

ating mechanism which is accessible to every set of contact springs in the four sections.

The quadrangular arrangement of the bank sections not only makes practicable a 55 switch in which the bank sections are readily removable for replacement and repairs, but also results in a much smaller structure for a given number of lines accommodated than has been practicable heretofore, on account 60 of the fact that the operating mechanism employed therewith is greatly simplified.

Other features of this invention reside in the unique mechanism whereby the contact springs are operated to effect connections 65 between subscribers' lines and trunk lines. One of the latter features consists in the provision, for each set of contact springs, of an operating lever or bell crank adapted to slide on a guide member over the several 70 spring pile-ups in its respective sets of contact springs and in combination therewith of an electromagnetic device particularly adapted to operate the plunger in all of its positions. Another feature of the operating 75 mechanism resides in the combination with the operating levers, of two notched bars arranged to slide longitudinally and adapted to engage, by means of their notches, all the 80 idle operating levers and move them simultaneously into idle trunk positions wherein they can be operated to establish connections 85 between their respectively associated subscribers' lines and idle trunks.

With reference to the drawings, Fig. 1 is 85 a view of the switch in elevation, some parts being broken away to facilitate illustration; Fig. 2, is an end view showing the step-by-step driving mechanism whereby the contact operating devices are shifted from position 90 to position, relative to their several associated sets of contacts; and Fig. 3 is a section taken along the line 3, 3 of Fig. 1, illustrating the arrangement of the devices and the relative arrangement thereto, of the 95 contact operating mechanism.

The base 1, together with end plates 2 and 3 form a supporting structure on which are mounted all the elements of the switch. The terminal bank which constitutes one of the 100 novel features of this switch comprises two groups of contact springs, each mounted in

opposed parallel relation to the other. Each group comprises two strips of contact springs 4, 5 and 6, 7 respectively, and each strip comprises a bar 9 on each of which are mounted a plurality of sets of contact springs, each set comprising subscribers' line springs and trunk springs. Bars 9 are each attached by means of screws 8 to the end plates 2 and 3 whereby they are supported. The connecting wires for each strip of contact springs are run in an individual cable 10 to a terminal block 12 comprising terminals 11 and screws 13. The cable terminals at the terminal block ends are each provided with a punching 37 adapted to be inserted under the heads of screws 13.

It is clearly evident then that in the event of trouble in any of the contact springs, the strip in which the trouble is located may be quickly removed simply by loosening screws 13 of the terminal block associated with that strip and removing screws 8. Another strip of contact springs together with the cable may then be substituted for the faulty strip, the entire operation consuming but a small period of time. Traffic on the other three strips of the bank is not interfered with in the least, during the time that the faulty strip is being removed and replaced by another.

Ordinarily, line switches are adapted to accommodate 100 subscribers' lines and 10 trunk lines, this proportion being subject to change to meet different traffic requirements. In the present description, it is presumed that 10 trunks are to be provided. Referring to Fig. 1, it will be seen that the contact springs of each strip are arranged in groups of ten sets each. Each of these groups of ten sets of contact springs is associated with one subscriber's line, that is, the ten sets of springs are multiply connected to the same line. Each set of springs in a group is connected to a different trunk. Each trunk is connected to one set of springs in every subscriber's group. The subscribers' line springs and trunk springs are normally out of contact.

There is provided for each subscriber's group of contact springs an operating bell crank 18, each of which is mounted on a stationary rod 19 and adapted to slide thereon longitudinally of its strip of contact springs into operable relation with its several associated sets of contact springs individually.

Two parallel bars, 20 and 21 are each provided with a plurality of notches 22, one notch for each bell crank 18. These bars are mounted on the end plates 2 and 3 and adapted to slide thereon in a direction longitudinal of the strips of contact springs. Each bar 20 and 21 is provided with a follower 23 which engages a grooved path on

the periphery of cam 24. Rotation of cam 24 causes bars 20 and 21 to reciprocate, the two moving simultaneously in opposite directions. Cam 24 is mounted on a shaft 25 which is journaled in end plate 2 and bracket 26. Securely mounted on shaft 25 and rotatable therewith is ratchet wheel 27 which is operably associated with stepping pawl 28 pivotally mounted on armature 29. The electromagnet 30 associated with armature 29 is adapted to operate the latter to effect rotation of shaft 25 and cam 24.

Bell cranks 18 normally engage notches 22 and are moved from position to position relative to their several associated sets of contact springs by bars 20 and 21.

Mounted on end plate 2, concentric with shaft 25 is a commutator, comprising 10 stationary contact terminals 35 each insulated from the other and from the end plate 2. These stationary terminals are each associated with one of the ten trunks leading into the switch. A brush 37 insulatively mounted on shaft 25 and rotatable therewith is adapted to wipe over stationary contacts 35. The switch is so designed that brush 37 is always in contact with that terminal 35 which is associated with the trunk which is connected to the sets of contact springs before which the normal bell cranks are situated. Stationary terminals 35 are associated with the energizing circuit of electromagnet 30 in such a way that the magnet is energized whenever brush 37 makes contact with a terminal 35 associated with a busy trunk. Each time electromagnet 30 is energized it rotates shaft 25 together with cam 24 and brush 37 through an angle of 36°, that is, one tenth of a circle and accordingly steps brush 37 to the next succeeding terminal 35. Rotation of cam 24 through one step is just sufficient to move the normal bell cranks from one position to the next, relative to their several sets of contact springs. So long as brush 37 continues to make contact with stationary terminals 35 which are associated with busy trunks, electromagnet 30 will continue stepping ratchet wheel 27 around. When brush 37 is finally brought into engagement with a stationary terminal 35 associated with an idle trunk, the circuit of electromagnet 30 is broken and the mechanism is brought to a standstill. All the normal bell cranks are then positioned before the sets of contact springs which are associated with idle trunks.

For each bell crank there is provided an electromagnet 14, each of which has an armature 17 which engages the bell crank in all of its several positions and which is adapted to engage the bell crank upon the energization of the electromagnet to effect the operation of the contact springs. Elec-

tromagnets 14 are each associated with a subscriber's lines and are operable upon the initiation of calls on their respective lines.

The electromagnets 14 are mounted on bars 5 15 which extend between end plates 2 and 3 and which are provided with angle members 16, whereby they are attached to the end plates.

Upon the initiation of a call on a subscriber's line, electromagnet 14 associated therewith is energized and draws up its armature 17. Armature 17, engaging bell crank 18, rotates the latter about rod 19, causing an arm thereof to engage and operate the set of contact springs before which it is, at the time, situated. The other arm of the bell crank which is normally connected with its notch 22 in one of the sliding bars 20 or 21 is withdrawn therefrom.

15 20 Operation of the contact springs established a connection between the calling subscriber's line and a trunk and further established an energizing circuit from electromagnet 30 whereupon the latter draws up its armature 25 29 which steps ratchet wheel 27, shaft 25, brush 37 and cam 24 forward one step. All the normal bell cranks are thereby moved to their next succeeding position. If the trunk connected with the contact springs in the latter position is idle, the aforementioned mechanism will stop, but if the trunk should be busy, electromagnet 30 will again be energized to step the mechanism to the next position, and so forth, until a position associated with an idle trunk is found.

Two plates 32 and 33 are provided with notches on their two edges for engaging the bell cranks in their operated positions and prevent further longitudinal displacement thereof until they again engage their notches in bars 20 and 21. Inasmuch as the bars 20 and 21 are moved immediately after the initiation of a call, the notches 22 are usually not in line with their respective bell cranks when the latter are released at the termination of the call. The locking plates 32 and 33 continue to engage the bell cranks until they actually drop into their notches in the bar, thus preventing 45 50 the bell cranks being moved by the frictional engagement of the bars therewith.

Referring to Fig. 3, the two upper bell cranks are seen to be engaging their notches in bar 20 in which position they are adapted to move with the bar. The bell crank in the lower left-hand position is seen to be disengaged from its notches in bar 21 and engaged by one of the notches in locking plate 32. The armature 17 associated with 55 60 the latter bell crank is in normal position, the call having terminated which resulted in the releasing of the bell crank. When the bar 21 is moved sufficiently the latter bell crank automatically drops into its associated 65 notch 22 and remains in operable relation

with said bar until reoperated by its respective armature 17 through the origination of a call.

What is claimed is:

1. In a switching mechanism, a contact operating mechanism and a terminal bank, comprising two groups of multiple contact strips, each group comprising two strips, each strip comprising a plurality of sets of contacts, the two strips in each group occupying an identical angular position and the two groups arranged in parallel relation on opposite sides of said operating mechanism. 70

2. In a switching mechanism, a bank of operable terminal contacts, a duplex operating mechanism for said contacts, said bank comprising two groups of strips of movable contacts, each group comprising two strips, each of said strips comprising a plurality of sets of said contacts and each strip in each group occupying an identical angular position, and the two groups arranged in parallel relation in opposite sides of said operating mechanism. 80 85

3. In a switching mechanism, a plurality of sets of contacts arranged in rows, a duplex mechanism for operating said contacts comprising a plurality of stationary bars, a plurality of operable members arranged on each of said bars, means for driving said members in a movement axially along said bars, means for operatively engaging said members, said means when operated being effective to cause interengagement between 90 95 100 said contacts.

4. In a switching mechanism, a plurality of sets of contact springs situated in a row, an operating bell crank for said contact springs arranged to slide forward and back longitudinally of said row and adapted to be positioned in operable relation to the several sets of contact springs individually, a member adapted to engage said bell crank when the latter is in normal position and move therewith longitudinally of said row of contact springs, an electromagnet, an armature for said electromagnet operable to disengage said bell crank from said member and to engage said bell crank with any said sets of contact springs individually, a locking device provided with a plurality of notches, one for each set of contact springs, said notches adapted to engage said bell crank when the latter is engaged with any 110 115 120 of said sets of contact springs, and prevent further longitudinal movement thereof until said bell crank is again engaged by said member, driving means for said member, and means for controlling the operation of said driving means.

5. In a switching mechanism, a plurality of sets of contact springs situated in a row, an operating bell crank for said contact springs arranged to slide forward and back 125 130

- longitudinally of said row and adapted to be positioned in operable relation to the several sets of contact springs individually, one arm of said bell crank being arranged 5 to engage and operate said contact springs, a notched bar adapted to engage by its notch a second arm of said bell crank when the latter is in normal position, said notched bar movable forward and back longitudinally of said row, an electromagnet, an armature for said electromagnet operable to move said bell crank, upon energization of said electromagnet, to disengage it from the notch in said notched bar and to engage it 10 with any of said sets of contact springs before which it may be positioned to effect operation of said contact springs, a notched plate adapted to engage said bell crank when operated in any of its positions and prevent 15 further longitudinal movement thereof until said bell crank is again engaged by the notch in said bar, driving means for said notched bar, and means for controlling the operation of said driving means.
- 20 6. In a line switch, an operating mechanism, two parallel groups of contact springs, situated on opposite sides of said operating mechanism, line conductors and trunk conductors multiply connected with said contact springs, operating levers adapted to be moved from position to position relative to said contact springs, a notched bar adapted to engage and move said operating levers into their several operative positions relative to said contact springs, electromagnetic means responsive to calls initiated on said line conductors for operating said operating levers to effect operation of said contact springs, and means for restraining said operating levers from further displacement when operated and thereafter until said operating levers are again engaged by said notches, means for driving said bar, and means for selecting idle trunks.
- 25 7. In a line switch, an operating mechanism, two parallel groups of contact springs situated on opposite sides of said operating mechanism, each group comprising two strips of contact springs and each strip comprising a plurality of sets of contact springs situated in a row on a common plane, the two strips in each group being arranged on a common frame but individually removable therefrom, said operating mechanism comprising a bell crank for each set of said contacts and each adapted to be moved from position to position relative to the several sets of contact springs in their respective strips, a pair of bars arranged in parallel relation to each other, notches in said bars, one for each bell crank, whereby said bell cranks are engaged when not operated and caused to move with said bars, means for reciprocating said bars longitudinally of 30 said strips, electromagnetic means to disengage said bell cranks from their respective notches in said bars and to engage said bell cranks with said contact springs to effect operation thereof, a pair of notched plates, one for each group of contact springs, each adapted to engage the bell cranks associated with their respective groups when operated to engage said contact springs and to restrain said bell cranks from further displacement longitudinally of their respective rows of 35 contact springs until said bell cranks are again engaged by the notches in their respective bars.
8. In a line switch, a supporting member, two parallel bars slidably mounted on said supporting member, a rotatable cam adapted to reciprocate said bars simultaneously in opposite directions, notches in each of said bars, bell cranks slidable in a direction parallel to said bars, said bell cranks each normally engaging one of said notches, and movable by said bars when so engaged, electromagnetic means for rotating said cam, a terminal bank operably associated with said bell cranks, said terminal bank comprising a plurality of sets of contact springs, a locking plate provided with a plurality of notches, one for each set of contact springs, said locking plate adapted to engage said bell cranks, when the latter are operated to engage said contact springs, and prevent further displacement of said bell cranks by said bars until said bell cranks are again engaged by the notches in said bars, and a second electromagnetic means operable to move said bell cranks to engage and operate said contact springs and to disengage the notches in said bars.
9. In a telephone exchange, a group of subscribers' lines, a group of trunk lines, a terminal bank for said lines in which each of said subscribers' lines is associated with each of said trunk lines, said terminal bank comprising two parallel groups of contact springs situated in opposing relation one to the other, each group comprising two parallel strips of contact springs, and each strip comprising a plurality of sets of contact springs situated in a row on a common plane, each of said subscribers' lines connected to a consecutive series of sets of contact springs in one of said strips, and each of said trunk lines connected to a different set of each subscriber's sets of contact springs, a plurality of bell cranks, one for each subscriber's line, said bell cranks adapted to be moved into operable relation with each of its associated sets of contact springs, a pair of notched bars, each adapted to engage by its notches, a plurality of said bell cranks when the latter are non-operated, means for reciprocating said bars together with the bell cranks engaged therewith in a direction parallel to said strips of contact springs, a plurality of electromagnets, one for each bell 40
- 45 10. In a telephone exchange, a group of subscribers' lines, a group of trunk lines, a terminal bank for said lines in which each of said subscribers' lines is associated with each of said trunk lines, said terminal bank comprising two parallel groups of contact springs situated in opposing relation one to the other, each group comprising two parallel strips of contact springs, and each strip comprising a plurality of sets of contact springs situated in a row on a common plane, each of said subscribers' lines connected to a consecutive series of sets of contact springs in one of said strips, and each of said trunk lines connected to a different set of each subscriber's sets of contact springs, a plurality of bell cranks, one for each subscriber's line, said bell cranks adapted to be moved into operable relation with each of its associated sets of contact springs, a pair of notched bars, each adapted to engage by its notches, a plurality of said bell cranks when the latter are non-operated, means for reciprocating said bars together with the bell cranks engaged therewith in a direction parallel to said strips of contact springs, a plurality of electromagnets, one for each bell 110
- 50 11. In a telephone exchange, a group of subscribers' lines, a group of trunk lines, a terminal bank for said lines in which each of said subscribers' lines is associated with each of said trunk lines, said terminal bank comprising two parallel groups of contact springs situated in opposing relation one to the other, each group comprising two parallel strips of contact springs, and each strip comprising a plurality of sets of contact springs situated in a row on a common plane, each of said subscribers' lines connected to a consecutive series of sets of contact springs in one of said strips, and each of said trunk lines connected to a different set of each subscriber's sets of contact springs, a plurality of bell cranks, one for each subscriber's line, said bell cranks adapted to be moved into operable relation with each of its associated sets of contact springs, a pair of notched bars, each adapted to engage by its notches, a plurality of said bell cranks when the latter are non-operated, means for reciprocating said bars together with the bell cranks engaged therewith in a direction parallel to said strips of contact springs, a plurality of electromagnets, one for each bell 115
- 55 12. In a telephone exchange, a group of subscribers' lines, a group of trunk lines, a terminal bank for said lines in which each of said subscribers' lines is associated with each of said trunk lines, said terminal bank comprising two parallel groups of contact springs situated in opposing relation one to the other, each group comprising two parallel strips of contact springs, and each strip comprising a plurality of sets of contact springs situated in a row on a common plane, each of said subscribers' lines connected to a consecutive series of sets of contact springs in one of said strips, and each of said trunk lines connected to a different set of each subscriber's sets of contact springs, a plurality of bell cranks, one for each subscriber's line, said bell cranks adapted to be moved into operable relation with each of its associated sets of contact springs, a pair of notched bars, each adapted to engage by its notches, a plurality of said bell cranks when the latter are non-operated, means for reciprocating said bars together with the bell cranks engaged therewith in a direction parallel to said strips of contact springs, a plurality of electromagnets, one for each bell 120
- 60 13. In a telephone exchange, a group of subscribers' lines, a group of trunk lines, a terminal bank for said lines in which each of said subscribers' lines is associated with each of said trunk lines, said terminal bank comprising two parallel groups of contact springs situated in opposing relation one to the other, each group comprising two parallel strips of contact springs, and each strip comprising a plurality of sets of contact springs situated in a row on a common plane, each of said subscribers' lines connected to a consecutive series of sets of contact springs in one of said strips, and each of said trunk lines connected to a different set of each subscriber's sets of contact springs, a plurality of bell cranks, one for each subscriber's line, said bell cranks adapted to be moved into operable relation with each of its associated sets of contact springs, a pair of notched bars, each adapted to engage by its notches, a plurality of said bell cranks when the latter are non-operated, means for reciprocating said bars together with the bell cranks engaged therewith in a direction parallel to said strips of contact springs, a plurality of electromagnets, one for each bell 125
- 65 14. In a telephone exchange, a group of subscribers' lines, a group of trunk lines, a terminal bank for said lines in which each of said subscribers' lines is associated with each of said trunk lines, said terminal bank comprising two parallel groups of contact springs situated in opposing relation one to the other, each group comprising two parallel strips of contact springs, and each strip comprising a plurality of sets of contact springs situated in a row on a common plane, each of said subscribers' lines connected to a consecutive series of sets of contact springs in one of said strips, and each of said trunk lines connected to a different set of each subscriber's sets of contact springs, a plurality of bell cranks, one for each subscriber's line, said bell cranks adapted to be moved into operable relation with each of its associated sets of contact springs, a pair of notched bars, each adapted to engage by its notches, a plurality of said bell cranks when the latter are non-operated, means for reciprocating said bars together with the bell cranks engaged therewith in a direction parallel to said strips of contact springs, a plurality of electromagnets, one for each bell 130

crank, an armature for each electromagnet, said armatures adapted to operate their associated bell cranks to effect operation of said contact springs to connect said sub-
scribers' lines and trunk lines, and to disengage said bell cranks from the notches in said bars, a pair of locking plates, each associated with one of said groups of contact springs, operable to engage said bell cranks

when operated and to prevent displacement thereof until said bell cranks are restored to engagement with their respective notches in said bars and means for selecting idle trunks.

In witness whereof, I hereunto subscribe my name this 27th day of August A. D., 1920.

CHARLES DONAT RICHARD.
